SHUTTER MECHANISM

Robert D. Dening, Long Beach, Calif.

Application September 1, 1945, Serial No. 613,996

7 Claims. (Cl. 2-8)

1

This invention relates to shutter mechanism for use in connection with welder's helmets, goggles, and the like.

In the helmets or goggles ordinarily used, the inspection apertures are permanently closed by a light screening shield, and it is necessary for the operator to reach up to raise the entire helmet or the goggles above the level of his eyes, when unobstructed observation or inspection is necessary. This is a slow and cumbersome operation, seriously delaying and affecting a smoothly running course of operation.

It is the general object of my invention to provide in such helmet or goggles a movable light screening shield. More particularly, it is my object to provide a very light, compact, and conveniently operable mechanism for moving such shield. A further object is to provide a slidable screen which is constructed and connected for movement in response to suction and blow of the operator's mouth through a tube attached to the device.

Other objects and the many advantageous features of the invention will be best understood upon perusal of the following detailed description, and drawings are hereto appended in which preferred forms of the invention are shown.

In the drawings:

Fig. 1 is a front view of a goggle structure embodying the invention, and with parts thereof broken away for the sake of clearness;

Fig. 2 is an endview of the device with a portion thereof broken away in order better to illustrate the interior mechanism thereof;

Fig. 3 is a front view showing a somewhat modified form of the invention;

Fig. 4 is a cross-sectional endview showing the device of the invention constructed for attachment to a welder's helmet.

The structure of Figs. 1 and 2 comprises right 40 and left goggles 1 and 2, which functionally may be exactly alike. Description of one will, for this reason, pertain equally to the other and structural differences will be fully discussed below. The general outline of the lower portion of the goggles follows the design of the conventional eyecups, the outer side edges of which are extended, substantially as indicated at 1^a, and 2^a, to form the usual protective, light excluding blinders. The goggles constitute frames within which are seated conventional welding lenses or eye shields 3. The framing within which each lens is seated comprises two vertically divided, shallow half-portions 4, 5 which, by means of screws 6 are combined to form therewithin an 55

2

oblong chamber 7, and the lens is slidably fitted within the lower part thereof.

The upper part of the chamber is shown occupied by an inflatable and deflatable member 5 in the form of a thin, elastic rubber bag 8, the neck 9 of which is anchored in a recess formed at the top of the chamber. The bottom of the bag is at 10 shown cemented or otherwise suitably fastened to the upper edge of the lens. An 10 air passage 11, at the top of the framing, communicates with the passage through the neck 9 of the bag, and a light, flexible air hose 12 is suitably fitted into this passage. The hose terminates in a mouthpiece 13 which the wearer, for 15 convenience, may retain in his mouth during welding operations.

As stated, the lens normally rests within the bottom of the framing so as to shield the eyes of the welder who, at any time, by suction 20 through the hose 12 may draw the lens upward substantially into the position indicated in Fig. 2. The suction causes the bag to collapse into the deflated position shown in this view, and it may be found preferable in order for the bag 25 to fold up evenly and smoothly, to cement the upper half-portion thereof to the casing wall. It may also be found advantageous to provide a narrow recess 14 in the chamber wall, within which any minute portion of the bag material 30 may gather when the bag is collapsed to raise the lens. In order to make room for the bag material, it is required slightly to enlarge the space within the upper portion of the chamber, and when carefully fitted, it is found that the 35 lens will remain in elevated position until, by a blow through the hose, it is forced back into normal position.

It was above stated that the two goggle frames may be substantially alike, and the only difference is that one of the frames is extended, as indicated at 16, to receive a flexible tubing 17, operatively to interconnect the two frames. This completes the device, except that a clear-glass lens may be placed in front of the eye shield, 45 substantially as indicated at 18 and as usual in practice.

In Figs. 3 and 4, the device of my invention is shown applied to a welder's helmet 20 and, in place of two, a single frame is employed to support a full width lens or eye shield 21 and clear glass lens 28. This frame is made similar to the goggle frame, in two half-portions 22, 23, which may be riveted to the helmet in the conventional manner, or may be fastened thereto 50 by means of screws 24, so that it may be taken

apart at any time for cleaning or lens replacement. But while the suction bag 25 necessarily is wider, the connections thereto and the operation thereof may remain substantially as above described. The mouthpiece 26 may, if preferred, be mounted rigidly on the inner wall of the helmet in proper position relative to the mouth of the user.

It is seen from the foregoing that I have provided a compact and sturdy shutter mechanism, which may be embodied into goggles or helmets without inconvenience to the wearer thereof and which may be operated by suction through the mouthpiece, thus leaving both hands free and the eyes of the welder fixed on the work. But while the drawings are illustrative of my invention, they do not necessarily represent the best engineering practice, and modifications of shapes and arrangements, within the scope of the claims hereto appended, may be embodied therein.

I claim:

1. A shutter mechanism for a welder's helmet or goggles comprising, a framing vertically divided into two shallow portions, means for clamping the two portions together, an eye shielding lens fittingly seated within the lower portion of the framing, an inflatable and deflatable member within the upper portion of the framing and operatively connected to the upper edge of the lens, there being recesses formed at the top of the two frame portions to provide a conduit communicating with the said member, and an air hose seatable in said conduit, said hose terminating in a mouthpiece, suction through which causes the member to become deflated and to draw the lens into the upper portion of the framing.

2. A shutter mechanism for a welder's helmet or goggles comprising, a framing vertically divided into two shallow half-portions, a lens fittingly seated within the lower portion of the framing, a flat circular inflatable bag mounted within the upper portion of the framing and operatively connected at the bottom thereof to the upper edge of said lens, and an air hose attachable to the framing and communicating with said bag, suction through said hose causing the bag to collapse and to draw the lens into the upper portion of the framing, there being a narrow recess in the inner wall of the framing substantially diametrically across the bag for receiving any minute surface material thereof as the bag reaches collapsed position.

3. A shutter mechanism for goggles consisting of two framings, each comprising a frame vertically divided into two shallow half-portions providing a single chamber therebetween, an eye shielding lens fittingly seated within the lower portion of each chamber and movable into the upper portion thereof, an inflatable and deflatable member mounted within the upper portion of each chamber and operatively connected to the upper edge of the lens seated therein for moving the lens into said upper frame portion, there being a recess in the upper portion of one of the frames forming a conduit leading into the inflatable member seated therein and a recess

traversely extending through the upper portion of the other frame to form a conduit connecting with the inflatable member seated therein, a flexible tube operatively interconnecting the two conduits, and a flexible air-tube seated in the open end of the said transverse conduit.

4. A shutter mechanism for a welder's helmet or goggles comprising, a framing vertically divided into two shallow half-portions providing a single chamber therebetween, an eye shielding lens fittingly seated within the lower portion of the chamber and movable into the upper portion of the chamber, an inflatable and deflatable member within the upper portion of the chamber and operatively connected to the upper edge of said lens, and an air conduit attachable to the framing and communicating with said member.

5. A shutter mechanism for a welder's helmet or goggles comprising, a framing divided into two half-portions providing a single vertically directed chamber therebetween, an eye shielding lens fittingly seated within the lower portion of the chamber and movable into the upper portion of the chamber, an inflatable and deflatable member within the upper portion of the chamber and operatively connected to the upper edge of said lens, and an air conduit attachable to the framing and communicating with said member.

6. A shutter mechanism for a welder's helmet or goggles comprising, a framing vertically divided into two shallow half-portions providing a single chamber therebetween, an eye shielding lens fittingly seated within the lower portion of the chamber, there being an aperture through the lower portion of the framing in registration with and somewhat smaller than the said lens, an inflatable and deflatable member mounted within the upper portion of the chamber and operatively connected to the upper edge of said lens, and an air hose attachable to the framing and communicating with said member.

7. A shutter mechanism for a welder's helmet or goggles comprising, a framing vertically divided into two shallow half portions providing a single chamber therebetween, means for clamping the two portions together, an eye shielding lens fittingly seated within the lower portion of the chamber, there being an aperture through the lower portion of the framing in registration with and somewhat smaller than said lens, an inflatable and deflatable member mounted within the upper portion of the chamber and operatively connected to the upper edge of the lens, an air hose attachable to the framing and communicating with said member, and a clear glass lens in the aperture of the framing in front of said eye shielding lens.
